CONTINUOUS INDUCTIVE TRAIN CONTROL SYSTEM

Filed June 12, 1926

UNITED STATES PATENT OFFICE.

WALTER W. WENHOLZ, OF ROCHESTER, NEW YORK, ASSIGNOR TO GENERAL RAILWAY SIGNAL COMPANY, OF ROCHESTER, NEW YORK.

CONTINUOUS INDUCTIVE TRAIN-CONTROL SYSTEM.

Application filed June 12, 1926. Serial No. 115,548.

This invention relates to the signaling and the automatic control of trains, and more particularly concerns an arrangement of wayside circuits and devices for a combined system of this type.

When a system of automatic train control of the three-position continuous inductive type is applied to a railway system, the roadside equipment which must be provided 10 is necessarily rather elaborate and expensive.

In a system of this type, two distinct alternating currents are employed for transmitting influence corresponding to traffic conditions to a moving vehicle, one current, 15 termed the track phase current, flowing in the two track rails of each of the usual track blocks in series; and the other current, termed the line phase current, flowing in the two track rails in multiple. It is necessary 20 to provide a line wire for the return of the line phase current from one end of each block to the other, and where the blocks are very long and are divided into one or more cut sections, to provide for the return of 25 this line wire to the track rails at certain points. The expense of providing this line wire is quite considerable and is a distinct disadvantage to the three-position continuous inductive system.

30 With the above and other considerations in mind, it is proposed in accordance with the present invention to provide a system of trackway circuits and devices for an automatic train control system of the three-position continuous inductive type in which the current for the line phase train control circuit is returned over the control wires of the usual three-position block signaling system.

40 Other specific objects, advantages and characteristic features of the invention will become apparent as the description thereof progresses.

In describing the invention in detail, reference will be made to the accompanying drawing, in which;

Fig. 1, represents in a diagrammatic manner the wayside circuits and devices for an automatic train control system comprising 50 the present invention, together with a simplified representation of one form of car-carried apparatus for use therewith; and

Fig. 2, shows a modification of the trackway circuits for use in connection with the 55 system of the invention.

Referring to the drawings, the track rails 1 have been shown divided into the usual blocks by the insulating joints 2, the block I and the ends of the two adjacent blocks H and J having been shown. The block I 60 is assumed to be of such length that it has been divided into two cut sections, I^a and I^b, it being understood that this block or any other block might be divided into as many cut sections of the desired length as might 65 be found advisable.

The system chosen for the purpose of illustration is of the type employing the well known "point B" described in the application of Howe and Bushnell, Ser. No. 653,898, filed July 26, 1923. Between this point B and the exit end of the block the line phase current is cut off from the track rails, when dangerous traffic conditions exist in the next block in advance, the distance 75 between this point B and the entrance end of the danger block corresponding approximately to an average safe breaking distance for a train traveling at a restricted or medium speed. In the system shown in the 80 present application this "B point" is the point defined by the location of the resistance 57.

The signaling system shown is of the well known alternating current automatic block 85 three-position type, and as this system is well known to those skilled in the art and as this invention does not concern certain details of the signal circuits, devices and the operation thereof, only a simplified 90 showing and a brief description of this system will be given herein.

As the various devices and the general arrangement of the circuits in the various blocks and cut sections are substantially 95 identical, like reference characters having distinctive exponents have been used to designate the corresponding elements in the various blocks. The letters B and C have been used to designate the positive and negative 100 terminals of a suitable source of direct current such as a storage or primary battery.

Alternating current track relays 3 of the well known type are connected across the track rails at the entrance end of each block 105 and of each cut section as shown, the current for operating these relays being supplied to the track rails at the exit ends of each block and cut section by the transformers 4, connected to the transmission 110

line 5, suitable reactances 6 being included in these supply circuits. The track circuit current also acts as the track phase train control current flowing in the two track rails in series.

Suitable wayside signals of the semaphore, color light or other type are preferably used in connection with the system of the present invention, and the well known semaphore type of wayside signals have been illustrated in the drawing in a conventional manner at Z. These signals are controlled by the operation of two alternating current relays, the track relay 3 at the entrance end of each block and the home and distant relay HD. The energization of the track relay 3 through the track rails of the transformer 4 has been described above. The home and distant relay HD is energized through the line wires 8, 9, 10, 11, 12 and 13 and the transformer 14 through a circuit which will be traced hereinafter. The home and distant relay HD is provided with a polar contact finger 15 which completes an energizing circuit for the direct current line relay 16 when in either of its energized positions as shown, the circuit for energizing this line relay 16 being traceable as follows:—from the battery terminal B, through the signal-operated contact finger 17 and its stationary contact 18, wires 19 and 20, stationary contact and contact finger 15 of the home and distant relay HD, and wire 21° through the winding of the line relay 16 to the battery terminal C.

Although the devices for operating the wayside signals in accordance with the energization and de-energization of the track relay 3 and the home and distant relay HD have not been shown, it should be understood that when the track relay 3 is energized and the home and distant relay is energized with current of normal polarity, the wayside signal Z gives a clear or proceed indication; that when the track relay 3 is energized and the home and distant relay HD is energized with a current of reverse polarity, the wayside signal Z gives a caution or medium speed indication; and that with the track relay 3 de-energized, the home and distant relay HD is de-energized, or both of these relays in the de-energized condition, the wayside signal Z gives a danger or stop indication.

A railway vehicle has been conventionally represented in the block H by the wheels and axles 23, the normal direction of traffic being indicated by the arrow. It should of course be understood that any suitable type of receiving and control apparatus may be employed in connection with this vehicle. In the drawings, an extremely simplified system of car-carried control apparatus has been conventionally illustrated, it being assumed that this system may be expanded

and changed in various ways without departing from the spirit of the invention. Two sets of inductive receiving coils 24 and 25 are provided on the vehicle, being carried in inductive relation to the track rails 1. The receiving coils 24 are carried in front of the leading axle of the vehicle and are connected in such a manner that voltages induced therein by alternating currents flowing in opposite directions in the two track rails are additive. The receiving coils 25 are carried behind one or more of the wheels and axles of the vehicle, preferably in the rear of the first vehicle of a train, and are connected in such a manner that voltages induced therein by alternating currents flowing in the same direction in the two track rails are additive. The receiving coils 24 and 25 are connected to suitable amplifying devices 26 and 27, preferably of the well known audion tube type, whose out put circuits are connected respectively to the two phase windings 28 and 29 of a polyphase alternating current engine relay ER. The relay ER is of the type well known in train control and signaling practice and is provided with any suitable number of movable and stationary contacts connected in the various vehicle control circuits. In the simplified system shown, the engine relay ER is provided with two movable contact fingers 30 and 31 which operate to control the energization of suitable brake control devices.

The vehicle brakes may be controlled in any suitable manner and by means of any one of a number of well known devices adapted for this purpose. As the initiation of an automatic brake application is usually effected by the de-energization of some suitable electro-magnetic device, two brake control devices M and L have been shown, it being assumed that the de-energization of the device M initiates a brake application which enforces a medium speed, while the de-energization of the device L initiates a brake application which enforces a low speed.

Operation.

All of the devices and circuits in the drawings have been shown in their normal operating positions, that is, with clear traffic conditions existing in all of the blocks shown, and with the vehicle proceeding without automatic restriction in the block H. The engine relay ER is thus in its normal energized position, the medium speed brake control device M and the low speed brake control device L being energized through circuits which are obvious from the drawings.

Considering first the operation of the system with a train proceeding under clear traffic conditions, assume that the vehicle is proceeding in the block H with no train,

broken rail or other hazard in either of the blocks I or J. Under these conditions, track circuit and track phase train control current flows in the two track rails of the blocks H, 5 I or J in series, this current being supplied by the transformer 4 through a circuit which may be traced as follows: in the block H:— from the transformer 4°, wire 32 to one of the track rails 1, down the track rail 10 through the wheels and axles of the vehicle 23 and back through the other track rail 1, through wire 33, reactance coil 6° and wire 34 to the transformer 4°. The track circuit and track phase train control circuits for 15 the cut sections of the block I and for the block J are identical with the circuit just traced in connection with the block H, this current flowing through the track relays 3 when no train is located in these sections or 20 blocks. The line phase train control current flows in the two track rails of each of the blocks in parallel, the circuit for this current in the block I being traceable as follows:—from the secondary winding of the 25 transformer 14, wire 35, contact finger 36 and front contact of the line relay 16, wire 37, contact finger 38 and front contact of the line relay 16, wire 39, dividing at the balance resistance 40 and flowing through 30 the two track rails in multiple to the balance resistance 41, through wires 42 and 43 dividing again at balance resistance 44 and flowing in the two track rails in multiple to the balance resistance 45, uniting in the wire 35, 46, wire 10, front contact and contact finger 47 of the track relay 3^b, wires 12 and 13, front contact and contact finger 48 of the line relay 16, and wire 49 to the secondary winding of the transformer 14. With the 40 line and track phase train control currents flowing in the two track rails, the receiving coils 24 and 25 have voltages induced therein, these voltages are amplified by the amplifiers 26 and 27 and the engine relay ER is 45 energized in a normal direction, causing the energization of the medium and low brake control devices M and L and the train may proceed in the clear territory without automatic restriction.

50 It should be observed that under the clear conditions described above, the home and distant relay HD is energized by the transformer 14 through a circuit which may be traced as follows:—from the secondary 55 winding of the transformer 14, wire 35, contact finger 36 and front contact of the line relay 16, wires 50 and 11, contact finger 51 and front contact of the track relay 3^b, wire 8, contact finger 52 and front contact of the track relay 3, wire 53, winding of the home 60 and distant relay HD, wire 54, front contact and contact finger 55 of the track relay 3, wires 9 and 10, front contact and contact finger 47 of the track relay 3^b, wires 12 and 65 13, front contact and contact finger 48 of

the line relay 16 and wire 49 to the secondary winding of the transformer 14. With the contact fingers 36, 38 and 48 of the line relay 16 in their attracted or energized positions, the current flowing through the circuit just traced are of normal polarity and energize the home and distant relay HD in a manner to move its contact finger 15 to the normal position as shown. Under these conditions, with the track relay 3 energized 70 and the home and distant relay HD energized with a current of normal polarity, the wayside signal Z gives clear or proceed indication, indicating to the engineer that the next two blocks in advance are unoccupied. 75

Considering next the conditions in a caution block, assume that a train is located in the block J, its wheels and axles shunting the track circuit current from the track relay 3¹ at the entrance end of this block and 80 causing this relay to assume its de-energized position. Under these conditions the home and distant relay HD¹ is de-energized by the retraction of the contact fingers 52¹ and 55¹ of the track relay 3¹, and the relay HD¹ 85 retracts its contact finger 15¹ to its de-energized position. The signal operated contact finger 17¹ disengages its stationary contact 18¹ and thus the energizing circuit for the line relay 16 is broken at two points, namely 90 at the signal operated contacts and at the contacts of the home and distant relay HD¹. The line relay 16, being de-energized, retracts its contact fingers 38, 36 and 48, and a circuit is completed for supplying a line 95 phase current of reverse polarity to the track rails of the block I, which circuit may be traced as follows:—from the secondary winding of the transformer 14, wire 35, contact finger 36 and back contact of the line 100 relay 16, wires 13 and 12, contact finger 47 and front contact of the track relay 3^b, wires 10 and 46, balance resistance 45 and the two track rails in multiple to the exit end of the section I^a, balance resistance 44, wires 43 105 and 42, balance resistance 41, the two track rails of the section I^b to the balance resistance 57, wire 58, back contact and contact finger 38 of the line relay 16, wires 37, 50 and 59, back contact and contact finger 48 110 of the line relay 16, and wire 49 to the secondary winding of the transformer 14. It will be noted that with the line relay 16 de-energized and its contact fingers 38, 36 and 48 retracted, the current supplied from the 115 transformer 14 to the home and distant relay HD at the entrance end of the block I will be reversed in polarity, the circuit for this reverse current being obvious from the drawings. 120

With this track relay 3¹ de-energized the wayside signal Z¹ at the entrance end of the block J assumes its danger or stop position. The reverse energization of the home and distant relay HD at the entrance end of the 130

block I causes the wayside signal Z at this point to give a caution indication.

As this vehicle under consideration enters the block I, the receiving coils 24 have the usual voltages induced therein by the track phase train control current flowing in the track rails of this block and supplied from the transformers 4 through obvious circuits. The receiving coils 25 however, have voltages of reverse polarity induced therein by the reverse line phase current flowing in the two track rails in multiple through the circuit traced above. The line phase winding 29 of the engine relay ER is therefore energized by a current of reverse polarity, and this relay swings to its reverse position, de-energizing the control device M but maintaining the control device L energized. The de-energization of the control device M en- forces a medium speed by suitable automatic means, which medium speed must be maintained by the vehicle as it proceeds in the block I if an automatic brake application is to be avoided. When the vehicle reaches the point B in the block I, the line phase train control current no longer flows in the track rails, the circuit for this line phase current having been traced above, and the receiving coils 25 do not have voltages induced therein. This causes the de-energization of the line phase winding 29 of the engine relay ER and this relay therefore assumes its de-energized position, causing the de-energization of both of the control devices M and L. The train must now proceed at a low speed to avoid an automatic brake application, this low speed being such that the train can be brought to a stop before the exit end of the block I is reached.

As the train now proceeds into the block J in which another train is located, the line phase train control currents again flow in the two track rails in multiple and induce voltages in the receiving coils 25. The track phase train control current however is shunted from the track rails in the block J by the wheels and axles of the train or vehicle in advance, and the engine relay ER therefore remains de-energized, enforcing the low speed control. As soon as the train in advance leaves the block J, the track phase train control current again flows in the track rails of this block and the following train is supplied with track phase current and with line phase current of reverse polarity and may proceed at the medium speed in the manner described in connection with the operation in a caution block.

Considering now the operation of the circuits and devices where cut sections are used, assume that a train is located in the exit section I^b of the block I. Under these conditions, the track phase and track circuit current is shunted from the rails of this section I^b by the wheels and axles of the train,

and this track 3^b at the entrance end of this section is de-energized, retracting its contact fingers 51 and 47. The retraction of the contact fingers 51 and 47 causes the de-energization of the home and distant relay HD at 70 the entrance end of the block I, the energizing circuit for this relay having been traced above. The de-energization of the home and distant relay HD causes the wayside signal Z at the entrance end of the block I to give 75 its danger indication and also causes the de-energization of the line relay 16^a, thus reversing the line phase train control current in the block H, making this a caution block as described above. The de-energization of 80 the track relay 3^b also breaks the circuit for the line phase train control current in the first section I^a of the block I, this circuit having been traced above, thus causing the de-energization of the engine relay of any 85 vehicle which might be located in this section I^a. It is, of course, necessary that line phase control current be supplied to the train located in a section I^b provided clear traffic conditions exist ahead, and this line 90 phase current is supplied through a circuit which may be traced as follows:—from the secondary winding of the transformer 14, wires 49, contact finger 48 and front contact of the line relay 16, wires 13, 62 and 42, 95 balance resistance 41, the two track rails of the section I^b in multiple, balance resistance 40, wire 39, front contact and contact finger 38 of the line relay 16, wire 37, front contact and contact finger 36 of the line relay 100 16 and wire 35 of the secondary winding of the transformer 14. It is of course to be understood that the presence of a train or vehicle in the first section I^a of the block I will shunt the track circuit and track phase 105 train control current from the track relay 3, causing its de-energization, giving a danger signal indication and providing caution train control and signal conditions in the block H as described above.

Summarizing the operation of the circuits and devices in connection with blocks and cut sections, it is clear that a train located in any of the cut sections of a given block will cause danger traffic conditions to be transmitted by the train-control currents and to be indicated by the signal indications of that block and caution conditions to be transmitted and indicated in the first block to the rear thereof.

Referring to Figure 2, a slight modification of the trackway circuits has been shown, the various circuits and devices being designated by the same reference characters as those used in Figure 1.

In the modification shown in Figure 2, the line phase circuit in the track rails is connected to the line wires 9 and 12 of the signal control line through back contacts 60 and 61 associated with the contact fingers 55 and 47 125 130

of the track relays 3 and 3^b located at the entrance ends of each block and each cut section respectively.

The operation of the modification shown in Figure 2 is the same as that described above in connection with Figure 2 except for the fact that the line phase circuit is normally de-energized, this circuit being broken at the contacts 60 and 61 when the track 10 relays 3 and 3^b are energized. When a vehicle enters the block 1, the track relay 3 is de-energized, its contact finger 55 energizing the back contact 60 and completing the line phase circuit for the entrance 15 portion of this block, this circuit being traceable as follows:—from the secondary winding of the transformer 14, wire 35, contact finger 36 and front contact of the line relay 16 wire 37, contact finger 38 and front contact 20 of relay 16, wire 39, balance resistance 40, the track rails 1, balance resistances 41 and 44, the track rails 1, balance resistance 45, wire 46, back contact 60 and contact finger 55 of the track relay 3, wire 9, front contact and contact finger 47 of track relay 3^b, 25 wire 12, front contact and contact finger 48 of line relay 16, and wire 49 to the transformer 14. In a like manner, when the vehicle passes the insulating joints at the middle 30 of the block and enters the second section thereof, the track relay 3^b is de-energized and the line phase circuit for the exit section is completed through wire 62 back contact 61 and contact finger 47 of relay 3^b.

It will be readily apparent that the operation of the system shown in Figure 2 is identical with that of Figure 1 as regards the control of trains. The modification of Figure 2, however, has certain advantages over that of Figure 1. In the modification, no energy is consumed by the line phase circuit unless a train or vehicle is in the block, and for this reason a substantial saving in energy is effected. Also, 40 when the relay HD is energized, only one wire of its control circuit is grounded through a balance resistance at a time. In the system of Figure 1, under normal clear conditions, both line wires which carry 45 the control current for the relay HD are connected to balance resistance, and a small amount of energy is thereby lost through the ground. Thus the system of Figure 2 effects a considerable saving in wayside energy consumption, which is a distinct advantage in a 50 system of this type.

It is seen that a system has been provided by the present invention in which an economy in line wires has been effected by employing 60 the usual line wires of an automatic block signaling system for the return of the line phase train control current of the automatic train control system, thus using only two line wires to take care of the two systems. This 65 is of particular advantage in reducing the ex-

pense of wayside installations. The simplicity of the wayside circuits is also of advantage where it becomes necessary to break the line wires through switch box contacts in the well known manner to protect train travel 70 on the main line against an open switch: there being only two line wires to be controlled to give the proper signal and train control operation, the switch box contacts may be very simple and few in number. 75

The present invention has been described in a rather specific manner and in connection with an extremely simplified and more or less diagrammatic system of car carried train control apparatus. It should therefore be clearly understood that the invention is not limited to the particular showing used to illustrate its nature, and that various changes, additions and modifications might be made in this apparatus without departing from the spirit of the invention as defined by the appended claims. For instance, apparatus might be provided on the vehicle and on the trackway for placing the car-carried devices in an inactive condition for train travel over sections of trackway unequipped for automatic train control, means for reversing the connections to the receiving coils for vehicle travel with the tender leading might be provided and many other modifications or changes might be made. 95

What it is desired to secure by Letters Patent is:—

1. In an automatic train control system, in combination with track rails divided into blocks, signal control relays at the entrance end of each of said blocks, control wires for said relays extending from the entrance to the exit end of said blocks, and means for transmitting influences corresponding to traffic conditions to moving vehicles including an alternating train control current flowing in the two track rails in multiple and controlled in accordance with traffic conditions in advance, one of said control 100 wires for said signal control relays being connected to form a return path for said alternating train control current. 105

2. In an automatic train control system of the type in which control influences corresponding to traffic conditions ahead are continuously transmitted from the trackway to a moving vehicle by means of a train control current flowing in the two track rails in multiple, two line wires extending along the trackway, one of said line wires carrying current to control wayside signal control devices and the other line wire forming a return path for said signal control current and said train control current. 115

3. In combination with a section of railway trackway divided into blocks, wayside signals and polarized signal control relays at the entrance end of each block, means for controlling the polarization and energiza- 120 125 130

tion of said relays through line wires in accordance with traffic conditions in the said block and in the first block in advance, and means for transmitting influences corresponding to traffic conditions to a moving vehicle on the trackway including an alternating control current flowing in the two track rails in multiple, one of said line wires for said signal control relays also forming a return wire for said alternating control current.

4. In a system of railway signaling and automatic train control, in combination with a trackway divided into blocks and having certain of said blocks divided into cut sections, track relays at the entrance end of each of said blocks and of each of said sections, wayside signals and signal control relays at the entrance end of each of said blocks, line wires extending the entire length of said blocks, means for controlling the polarity of energization of said signal control relays through said line wires in accordance with traffic conditions in the first advance block, contacts on said track relays for opening said line wires when any one of said track relays is de-energized, and means for transmitting influences corresponding to traffic conditions to a moving vehicle comprising an alternating control current flowing in the two track rails in multiple and through one of said line wires, said means for controlling the polarity of energization of said signal control relays also controlling the polarity of said alternating control current.

5. In an automatic train control system, means for transmitting influences corresponding to traffic conditions from the trackway to a moving vehicle comprising, inductive receiving devices on the vehicle, an alternating control current flowing in the two track rails in series and an alternating control current flowing in the two track rails in multiple, and means for returning said alternating current flowing in the two track rails in multiple from one end of an insulated block of trackway to the other comprising a line wire, said line wire also acting to control the energization of wayside signal control devices.

6. In a system of railway signaling and automatic train control, in combination with track rails divided into blocks, trackway circuits comprising a track circuit current flowing in the two track rails of each block in series, a track relay at the entrance end of each block energized by said track circuit current, a polarized relay energized through a circuit controlled by said track relay, a line relay having an energizing

circuit controlled by said polarized relay, said line relay controlling pole changing contacts in the energizing circuit for the polarized relay in the next block in the rear, and an alternating train control current flowing in the track rails of each block in multiple, the polarity of said train control current being controlled by said line relay and the return path of said train control current being through part of the energizing circuit for said polarized relay.

7. Trackway apparatus for automatic train control and wayside signal control purposes comprising, a trackway divided into blocks each having a plurality of track sections, a track relay for each track section, a signal control relay at the entrance to each block controlled through a line circuit in accordance with the conditions of the track relays of said block and the signal control relay at the entrance of the next block, in advance, and a circuit for transmitting train control current consisting of two track rails in multiple of said block and said line circuit in series.

8. Trackway apparatus for automatic train control and wayside signal control purposes comprising, a trackway divided into blocks, a signal at the entrance to each block, a track relay at the entrance end of each block, a signal control relay associated with each signal, a line wire for controlling said signal control relay in accordance with traffic conditions in the next block in advance and including a front contact of the track relay of said block, and means for completing a train control circuit including the track rail of said block in series with said line circuit upon de-energization of said track relay.

9. Trackway apparatus for automatic train control and wayside signal control purposes comprising, a trackway divided into blocks, a signal at the entrance to each block, a track relay at the entrance end of each block, a polar signal control relay associated with each signal, a line wire including in series therewith a front contact of the track relay of a block for energizing the polar signal control relay with a current of relative polarity depending on traffic conditions in the next block in advance, and means for completing a circuit upon de-energization of said track relay including said line wire and a track rail in series having current flowing therein of a relative polarity depending on traffic conditions in the next block in advance.

In testimony whereof I affix my signature.

WALTER W. WENHOLZ.
